UNITED STATES PATENT OFFICE.

ROBERT McCULLY, OF PHILADELPHIA, PENNSYLVANIA.

STONE-BREAKER.

SPECIFICATION forming part of Letters Patent No. 566,088, dated August 18, 1896.

Application filed September 17, 1886. Serial No. 213,797. (No model.)

To all whom it may concern:

Be it known that I, ROBERT McCULLY, a citizen of the United States, residing at Philadelphia, in the county of Philadelphia and State of Pennsylvania, have invented certain new and useful Improvements in Stone-Breakers, of which the following is a specification, reference being had therein to the accompanying drawing, wherein the figure is a vertical section, partly in elevation, of a stone-breaking and ore-crushing machine embodying my improvements.

My invention has relation to crushing-mills having gyratory shafts and crusher-heads, having particular reference to the form of mills shown and described in Letters Patent of the United States issued to me on the 7th day of September, 1886, Nos. 348,757 and 348,758; and it has for its object the construction and combination of parts to increase the efficiency and durability of the mill.

My invention accordingly consists of the combination, construction, and arrangement of parts, as hereinafter described and claimed.

In the drawing, A represents the frame or easing of the mill, comprising a bottom plate B, chute or outlet chamber C, crushing-chamber D, and top plate E through which the ore or material is fed into the crushing-chamber D.

F indicates the gyratory shaft; G, the crusher-head mounted on said shaft and located within the chamber D.

In the top plate E is a bearing or opening e, having a cap or cover e' suitably fastened thereon. This bearing or opening is provided with vertical grooves e², in which are inserted bolts e³, passing up through the top plate e', and these bolts are provided with adjusting-nuts e⁴ or other equivalent devices e⁴. Upon the heads e⁵ of bolts e³ rests a continuous or solid sleeve e⁶, which has a bore tapering downwardly, as shown. Within this bore is a bushing e⁷, preferably made in sections and having inwardly-projecting top flanges e⁸ with concave under sides e⁹ to conform to the rounded end f of the head f' of shaft F. The outside of the bushing e⁷ has a taper corresponding to that of the bore of the sleeve e⁶, and is held to its position or bearing with sleeve e⁶ and shaft-head f' by a set-screw e¹⁰, which passes through the cover or cap e', as

shown. As the shaft-head f' and bushing e⁷ wear, the nuts e⁴ are adjusted to raise the sleeve e⁶ and draw or move the sections of bushing e⁷ together, or in close bearing with said parts, to compensate for such wear. The working faces d of the crushing-chamber have but a single taper or incline in the same direction from top to bottom, and they may be composed of sections, as shown, or otherwise constructed as desired. These working faces, as shown, have their lower edges resting upon the top surface of the chute-chamber C and near their upper edges are provided with a lug entering a corresponding recess in the walls of chamber D.

The crusher-head G is composed of a sleeve g, suitably cast or mounted on shaft F, and has two working faces g' g², reversely tapered. The taper of face g² corresponds to that of the crushing-faces d of chamber D, so that the faces g' act to break the material fed into chamber D and the faces g² to successively grind or crush said broken material.

Surrounding the opening c in the top c' of chute-chamber C is an elastic protector H, which is preferably made of rubber or leather. It is composed of an upper thick hub h, surrounding and hugging shaft F of a lower like hub h', having a shoulder h², which is sprung into and preferably loosely fits an annular slot in a flange c², surrounding opening c, and of a thin curved part h³, joining the hubs h h', so that it may revolve with the shaft and give to it vertical movement when adjusted. Said protector H with its hubs h and h' and thin curved part h³ is made in one piece preferably. Between the shaft F and its driving-wheel L is another protector I, of a construction similar to that of protector H, or it is composed of an upper and a lower hub i and i', respectively, joined by a thin curved part i². Its lower hub i' is, however, fitted into a grooved sleeve i³, loosely mounted upon wheel L and held in place by a cap or plate i⁴. The sleeve i³ and plate i⁴ for the lower hub i of protector I are provided to prevent undue wear of said hub i by the rotation of wheel L, but as said protector I may be connected to wheel L in various ways I wish it to be understood that in this application I broadly claim a protector having upper and lower hubs united by an intermediate thin curved part,

between a fixture of the breaker and the gyrating shaft.

The wheel L is provided with a sleeve l, having an eccentric bore, and the bottom 5 plate B has a bearing b, having oil-gutter and sediment-chamber b' and ducts b² b³, as fully described and claimed in applications filed of an even date herewith, Serial Nos. 213,795 and 213,796. The bottom of shaft F is provided with a removable cup or semispherical bearing k, and k' is a like bearing on a loose or removable bottom b⁴ for bearing b, for the knuckle or toggle lever step-bearing P. The removable socket-bearings k k' are 10 provided so as to admit of easy replacement when worn out. The bottom or plug b⁴ is preferably hollow or tubular in form and is provided with a stuffing-box b⁵ and a drip-cock b⁶ to drain off the oil from bearing b when desired. To facilitate this draining, an oil-duct k² is formed in bearing k'. The bottom b⁴ rests upon a plate m, which is held in 15 position by screws or bolts m', the heads m² of which have their bearing in the bottom of oil-gutter b', and the bolts pass down through vertical openings in the sides or walls of bearing b, through apertures in plate m, and have adjusting-nuts or equivalent devices m³, which are manipulated or turned to raise 20 and lower the shaft and crusher-head for varying the degree of fineness of the output or for other purposes. Whenever the shaft F is so adjusted, its top bearing or bushing e⁷ must be correspondingly adjusted, as above 25 described. Previous, however, to making any vertical adjustment for raising shaft F the set-screw e¹⁰ is raised to admit of such adjustment, as this screw is always set to prevent the shaft from rising or jumping up 30 while operating.

The head f' of the shaft F may be of any suitable configuration, but I prefer to make it cylindrical with a rounded top f, as shown, to avoid rubbing or grinding friction between 45 it and bushing e⁷.

It will be noted that the top shaft-bearing and its adjusting devices do not support the shaft, such support being solely effected by the step-bearing of the shaft.

The bottom b⁴ being tubular or hollow collects all the sediment and waste dripping into it from the parts in bearing b and the working parts above are immersed in pure or good oil.

The advantage of using the toggle P in connection with the adjustable supporting devices for the upper end of the shaft is that said devices take the weight of the shaft and crusher-head off of the toggle. Hence there is less friction at the bearings of the toggle, and as it is directed at an angle away from the grinding or working side of the crusher-head the same is free to assist in keeping the crusher-head to its work, as fully described in pending application of even date herewith, Serial No. 213,795.

In application Serial No. 213,795 I have

shown and claimed a specific form of removable and adjusting screw-bottom, which differs from that herein described in that the 70 lower bearing k' for the toggle is integral with or fixed on said bottom, which is shown as being solid, with an oil-duct running through it, which duct is not a sediment-chamber. In this application I broadly claim a removable 75 and adjustable bottom b⁴ irrespective of its construction with bearing for the lower end of toggle P, and also a hollow or sediment-chamber form of said bottom or plug and the combination therewith of a stuffing-box. 80 In another application, filed December 1, 1886, Serial No. 220,329, I have shown and claimed a specific form of screw-bottom or plug serving as a sediment-chamber. I do not herein claim the combination of 85 a gyratory shaft and its driving-wheel eccentric bore or bearing, the toggle P engaging the lower end of said shaft and so situated that it always points away from the most eccentric portion of the said wheel bore or bearing to cause said toggle to incline constantly 90 toward that part of the crusher-head which is in action, as the same is broadly claimed in another application of even date herewith, Serial No. 213,795. 95

In still another pending application of even date herewith, Serial No. 213,796, I have described and claimed a sleeve-bearing with adjusting devices combined with a set-screw for the top of the shaft, and I do not herein claim 100 the same broadly, but only specifically as set forth in the claims.

What I claim is—

1. In a gyratory stone-breaker, the combination of the gyratory shaft, having the straight 105 vertical-sided cylindrical head, f', of the semi-spherical-formed top, f, adapted to conform to the inner or bored faces of the flanges, e⁸ e⁸, of the sectional tubular bushings, the said sectional tubular bushings, e⁷ e⁷, inclined on 110 their outer faces, from above downwardly, the tubular sleeve, e⁶, surrounding the said bushings, provided on its inner side with the tapering face, inclined from above downwardly, adapted to fit the outer faces of the 115 said bushings, the top plate, E, having the bearing, or central hub, e, for the said tubular sleeve, e⁶, and raising, lowering and adjusting means, substantially as herein shown and described. 120

2. In a stone-breaker, the combination with shaft F, of driving-wheel L, protector I having upper and lower hubs i and i' and thin curved part i² uniting said hubs, a loose ring i³ on wheel L and fitting one of said hubs, and an annular plate i⁴ on wheel L engaging ring i³ substantially as set forth. 125

3. In a stone-breaker the combination with shaft F having driving-wheel with eccentric bushing of knuckle or toggle step-bearing P, 130 tubular bottom b⁴, plate m, and adjusting-bolts m', substantially as set forth.

4. In a stone-breaker, the combination of shaft F, having driving-wheel with eccentric

bushing adjustable tubular bottom b^4 , means for securing said bottom in place removable socket-bearings k k' and knuckle or toggle P, substantially as set forth.

5. In a stone-breaker, the combination of shaft F, having driving-wheel with eccentric bushing adjustable bottom b^4 , means for securing said bottom in place the latter having oil channel or drip b^6 , removable socket-bearings k k' , the latter having channel k^2 and knuckle or toggle P substantially as set forth.

6. In a stone-breaker the combination of gyratory shaft F, the knuckle or toggle P socket-bearing plate k' having passage k^2 and tubular bottom b^4 serving as a sediment-chamber and adjusting mechanism for said tubular bottom.

7. In a stone-breaker the combination of bottom plate B, having well b, the shaft F, tubular step-bearing b^4 , a socket-bearing plate k' at the top of bearing b^4 , adjusting mechanism for the latter and a knuckle or toggle P between said shaft and plate k' substantially as set forth.

25 8. In a stone-breaker the combination of bottom plate B having well b, adjustable tubular step-bearing b having stuffing-box b^5 , the bearing k' having passage k^2 gyratory shaft F and knuckle or toggle P between shaft 30 F and bearing b substantially as set forth.

9. In a stone-breaker the combination of a gyratory shaft, driving mechanism for said

shaft, a bottom plate B having a well b, perforated bearing-plate k' a removable and adjustable tubular bottom or plug for said bearing, knuckle or toggle P and a stuffing-box for said plug or bottom substantially as set forth.

10. In a stone-breaker, the combination of shaft F, wheel L having recess at or near its upper edge, and protector I having hubs i i' , rigid curved thin part i^2 between said hubs, and protector-hub i' having a swiveled connection with wheel L, substantially as set forth.

40 11. The flexible or elastic shield or protector I having hubs i i' rigid curved thin part i^2 between said hubs, and hub i' having a swiveled ring secured to it substantially as set forth.

45 12. In a stone-breaker the combination of a shaft, devices for gyrating said shaft, a flexible or elastic protector composed of top and bottom hubs and intermediate rigid curved thin part, one of said hubs engaging the shaft 55 and the other having a swiveled connection with a fixture of the breaker, substantially as set forth.

In testimony whereof I affix my signature in presence of two witnesses.

ROBERT McCULLY.
